GEORGE SYKES, OF PENRYN, CALIFORNIA, ASSIGNOR TO SYKES STANDARD FRUIT WRAP CORPORATION, OF PENRYN, CALIFORNIA, A CORPORATION OF CALIFORNIA.

DESIGN FOR PACKING AND DISPLAYING ROUND OBJECTS.

54,702.

Specification for Design.

Patented Mar. 9, 1920.

Application filed March 11, 1918. Serial No. 221,854. Term of patent 14 years.

To all whom it may concern:

Be it known that I, GEORGE SYKES, a citizen of the United States, and a resident of Penryn, in the county of Placer and State of California, have invented a new, original, and ornamental Design for Packing and Displaying Round Objects, of which the following is a specification, reference being had to the accompanying drawing, forming part thereof.

In the drawing:—

The figure illustrates a front view of the design as the package is presented to the public for display purposes.

What I claim is:—

The new and ornamental design for packing and displaying round objects, substantially as shown.

In testimony whereof, I have hereunto set my hand this 2nd day of March, 1918, in the presence of the two subscribed witnesses.

GEORGE SYKES.
